TORE GUSTAF EMANUEL LINDMARK, OF STOCKHOLM, SWEDEN.

ELASTIC-FLUID TURBINE.

SPECIFICATION forming part of Letters Patent No. 761,238, dated May 31, 1904.

Application filed June 27, 1902. Serial No. 113,529. (No model.)

To all whom it may concern:

Be it known that I, TORE GUSTAF EMANUEL LINDMARK, a subject of the King of Sweden and Norway, and a resident of Stockholm, 5 Sweden, have invented a new and useful Improvement in Elastic-Fluid Turbines, of which the following is a specification.

The invention relates to means for increasing the efficiency of the exhaust from an elastic-fluid motor and to means interposed between two of said motors for heating said exhaust during its passage from one motor to the other. If the working medium is steam or other vapor, such heating does not necessarily result in elevating the temperature of said exhaust; but it may also have for its object to dry the exhaust, according to circumstances.

My invention consists more particularly in 20 a compound steam-turbine in which the exhaust of the first wheel of the series is heated by means located within the passage traversed by said exhaust and before said exhaust enters the next wheel of the series to actuate the 25 same.

The accompanying drawing is a side elevation and partial longitudinal section of an apparatus embodying my invention.

The wheel-casing is made in two parts A 30 and A', secured together in any suitable way. The bed-plate projections B may be formed integrally with the lower portion A'. Upon two of said bed-plates are the standards C, which carry the bearings D for the wheel-shaft E, on which is the usual belt-pulley F. The middle portion of the shaft E is enlarged, 35 as shown at G. Adjacent to the head H of the casing and beginning on the left of the drawing is formed a chamber a, which communicates with the steam-inlet pipe T. By 40 means of the partitions b c d and the casing-head I there are also formed within the casing three annular chambers f g h. The chamber h communicates with the exhaust-pipe i. Fast 45 on the enlarged middle portion G of the wheel-shaft E is a hub j, which passes through flanged openings in the casing-heads H I. The wheel-bodies k l m may be formed integrally with this hub. Each wheel-body has 50 an annular opening o p q, surrounded by the

flange r s t. The partition b has an annular opening to receive the flange o with a steam-tight joint, and similar openings are formed in the partitions c d to receive the flanges p q. A pipe u passes through the wall of the casing and forms a coil in the chamber f, which coil surrounds the first wheel k and then passes to the chamber g and forms another coil around the wheel l and then passes out through the casing-wall. It will be seen from this construction that the successive wheels k l m together form a compound or multiple turbine. The steam-space in each wheel (from the first wheel of the series to the last) is progressively larger, so as to expose progressively greater 55 bucket areas to the increasing volume of the successive exhausts. The working steam thus passes, as indicated by the arrows 2, from the pipe T to the chamber a, thence to the annular opening o, to wheel k, thence to chamber 60 f, to the wheel l, to chamber g, to wheel m, and from the chamber h, surrounding that wheel, to the exhaust-outlet i, thus acting upon all of the wheels and setting them in rotation. Meanwhile live steam traverses the coils of 65 pipe u, as indicated by the arrows 1, and as a consequence the steam escaping from the wheel k into chamber f becomes heated before passing to wheel l, and the steam from wheel l also becomes heated in the chamber g before 70 passing to the wheel m.

I do not limit myself to the steam-pipe u, located within the passage or chamber between the wheels, as a heating means for the exhaust. I may use any other means disposed 75 in said passage competent to produce a like result—as, for example, an electrical heater of any known form or a gas-heater or any device for heating the steam by chemical reaction, all of which are broadly equivalents 80 of the steam-heater hereinbefore described. Neither do I limit myself to a compound steam-turbine of the specific type herein illustrated, since other forms of compounded steam-wheels are known.

I claim—

1. In combination with an elastic-fluid turbine-wheel of the outward-flow type and a casing therefor, a duct adapted to convey hot gases located within said casing and surround-

ing and receiving the direct impact of the escaping fluid jets from said wheel.

2. In combination with the wheels of a compound elastic-fluid turbine of the outward-flow type and a casing therefor containing chambers for said wheels, a continuous duct adapted to convey hot gases located within said casing and surrounding and receiving direct impact of the escaping fluid jets from said wheel.
- 10 3. In combination with the wheels of a compound elastic-fluid turbine of the outward-flow type and a casing therefor containing chambers for said wheels, a continuous duct adapted to convey hot gases located within said chambers and in spiral form therein; the said spirals respectively surrounding and receiving the direct impact of the escaping fluid jets from said wheels.
- 15

4. In combination with the wheels of a compound elastic-fluid turbine of the outward-flow type and a casing therefor containing chambers for said wheels, a continuous duct adapted to convey hot gases located within said chambers and in spiral form therein and also having intermediate portions extending outside 25 of said casing; the said spiral portions respectively surrounding and receiving the direct impact of the escaping fluid jets from said wheels.

In testimony whereof I have signed my name 30 to this specification in the presence of two subscribing witnesses.

TORE GUSTAF EMANUEL LINDMARK.
